UNITED STATES PATENT OFFICE.

THEODORE H. NELSON, OF CHICAGO, ILLINOIS.

BURGLAR-ALARM SYSTEM AND APPARATUS THEREFOR.

1,290,644.

Specification of Letters Patent.

Patented Jan. 7, 1919.

Application filed January 29, 1916. Serial No. 74,962.

To all whom it may concern:

Be it known that I, THEODORE H. NELSON, a citizen of the United States, residing at Chicago, in the county of Cook and State 5 of Illinois, have invented a new and Improved Burglar-Alarm System and Apparatus Therefor, of which the following is a specification.

My invention relates to an improved burglar alarm system designed particularly to 10 protect an outer doorway which must be used to secure access to the system, and it is an object of my invention to provide circuit connections and controlling mechanisms 15 so that by proper operation of the controlling mechanism by an authorized person the system is temporarily disabled so that the door may be opened without ringing the alarm. It is a further object of my invention 20 to automatically return the signaling system to its set condition by the subsequent closing of the door. While my system is applicable to burglar alarms it is also applicable to other purposes in which it is 25 desired to control an electric circuit so that by the operation of the controlling mechanism in a predetermined manner the circuit is maintained in one condition; whereas the 30 improper manipulation of the controlling mechanism leaves the circuit in another condition. Thus, for example, in a burglar alarm system the alarm circuit may be normally open and the proper operation of my controlling mechanism maintains said circuit 35 in its open condition notwithstanding the operation of the alarm contacts, or the burglar alarm system may have a normally closed circuit which is maintained in its closed condition by the proper operation of 40 my controlling mechanism when the alarm contacts are actuated subsequent to said operation of the controlling mechanism. Or again, other circuits may be similarly controlled, such, for example, as the ignition circuit 45 of an automobile so that the ignition circuit remains open even though the usual key switch be closed until the controlling mechanism characterizing my invention is actuated in the required manner.

50 The several drawings illustrating my invention are as follows:

Figure 1 is a diagrammatic drawing showing my system applied to an open circuit burglar alarm system,

55 Fig. 2 shows in a view similar to Fig. 1

the application of my system to a closed circuit burglar alarm system,

Fig. 3 shows in a view similar to Figs. 1 and 2 the application of my system to the ignition circuit of an automobile. 60

Fig. 4 shows in a vertical sectional view the detail construction of the controlling mechanism,

Fig. 5 shows the controlling mechanism in front elevation, 65

Fig. 6 shows the controlling mechanism in rear elevation with the casing removed, and

Fig. 7 shows the controlling mechanism in front elevation with the front plate removed.

Similar numerals refer to similar parts 70 throughout the several views.

Since the operation of my system depends in large part upon the controlling mechanism employed, I will first describe this mechanism referring particularly to Figs. 75 4, 5, 6 and 7. In these figures the casing 10, which is cylindrical in form, is secured by screws as indicated to the front plate 11 which supports by a plurality of posts 12 the insulating disk 13 which constitutes the 80 support for the contacts 14 and conducting ring 15, these contacts and conducting ring being located on the front side of the disk. The front plate 11 has extending rearwardly 85 from it a central boss 16 in which a cylindrical rod 17 is mounted so as to be freely rotatable. The inner end of the rod 17 has mounted upon it a contact blade 18 which is secured in place between a collar 19 and nut 20 carried by said rod. One end of the contact blade 18 is arranged to engage the contact ring 15 and the other end of said blade is arranged to engage desired ones of the contacts 14, the conducting ring and contacts being in different planes so that the 90 contact engaging end of the contact blade does not engage the conducting ring. In its normal position the contact blade 18 is held away from the contacts and conducting ring by a spring 21 located in a suitable recess in the front plate 11 between said plate and the inner face of the dial 22 rigidly secured to the outer end of the rod 17. The central portion of the dial 22 is formed into a hub 23 by which the dial may be rotated. 100 At its outer edge the dial has an inwardly extending flange 24 to increase the bearing surface between it and the cylindrical bore formed therefor in the front plate 11. The flange 24 has projecting rearwardly from it 110

a pin 25 for entering the holes 26 formed in the front plate to permit the dial to be pushed rearwardly only when the contact blade 18 is angularly aligned with desired ones of the contacts 14. The edge of the dial and the adjacent edge of the front plate are provided with graduations and suitable indications as, for example, numbers, so that the dial, rod and contact blade may be turned to bring the contact blade opposite any desired contact 14, for which condition, as a result of the coöperation of the pin 25 with the corresponding one of the holes 26, the dial may be pushed rearwardly against the action of the spring 21 to bring the contact blade 18 into engagement with the selected contact 14 and at the same time with the conducting ring 15 which serves to electrically connect the selected contact with said conducting ring. The pin 25 serves to prevent holding the dial 22 in its rearward position and sweeping the contact blade over the contacts one after the other and necessitates angular adjustment of the dial to a desired position before the dial can be moved to the rear to close the circuit controlled by the selected contact.

Since the controlling mechanism described is of necessity located on the outside of the room or building protected by the alarm system and therefore accessible to any one who desires to operate it, I provide against tampering with the system by the removal of the front plate in an attempt to disable the system by providing the safety springs 27 and 28 on the rear face of the disk 13, which springs in an open circuit system are normally separated from each other by the engagement of an insulating plug 29 carried by the spring 28 with the inner wall of the casing 10 so that when the front plate 11 and the parts carried thereby are removed from the casing the springs 27 and 28 come together, closing the desired circuit in a manner to be explained. Similarly for a closed circuit control system the safety springs are normally held in contact with each other as indicated in Fig. 2, and for this construction when the front plate is removed the contact springs 27 and 28 separate from each other opening the controlled circuit and giving the alarm.

In Fig. 1 I have shown an application of my controlling mechanism to an open circuit burglar alarm system, the controlling mechanism already described being provided with relay mechanism for controlling the alarm circuit, which relay mechanism forms a part of the control system whether used for an open circuit or a closed circuit burglar alarm, or whether used for any other circuit control. In this figure the wire 30 is connected with a desired one of the contacts 14 and also to one terminal of the winding of the relay 31, the other terminal of which is con-

nected with the negative terminal of battery 32, the positive terminal of said battery being connected to the common conductor 33. The wire 30 is also connected with the armature 34 of the relay 31. The wire 35 is connected with a desired one of the contacts 14 and with a second armature 36 of the relay 31, which armature coöperates with a make-contact 37 connected by wire 38 with one terminal of the winding of relay 39, the other terminal of which is connected with the negative terminal of battery 40, the other terminal of which battery is connected with the common conductor 33. The wire 38 is also connected with the armature 41 of the relay 39, and wire 42 is connected with another desired one of the contacts 14 and with a second armature 43 of the relay 39, which armature coöperates with a make-contact 44 connected by wire 45 with an armature 46 of relay 47, which relay is constructed so as to be sluggish in operation for a purpose to be described. The wire 45 is also connected with a break-contact 48 of the armature 49 of relay 50. The armature 49 is connected with one terminal of the winding of the relay 47, the other terminal of which is connected with the negative terminal of battery 51, the other terminal of said battery being connected with the common conductor 33. The negative terminal of the battery 51 is also connected with a second armature 52 of relay 47, which is provided with a make-contact 53 connected by wire 54 with a second armature 55 of the relay 50. The wire 54 is also connected with one terminal of the winding of the relay 50, the other terminal of said winding being connected by wire 56 with one of the door contacts 57 of the burglar alarm. The contact 58 of the burglar alarm coöperating with the contact 57 is connected by wire 59 with the common conductor 33. The armature 46 is provided with a make-contact 60 which is engaged by the armature when the latter is attracted, further motion of said armature after its engagement with the contact 60 serving to move the contact 60 away from the contact 61 with which it is normally in engagement. The contact 61 is connected by wire 62 with make-contacts 63 and 64 of armatures 34 and 41 respectively. The contact 60 is connected by wire 62' with the contact of armature *r* of relay R and the armature *r* is connected by wire 88 with the common conductor 33. The armature 55 is provided with a make-contact 65 connected with the negative terminal of battery 66, the other terminal of which is connected with the common conductor 33. A release wire 67 is connected with one or more of the contacts 14 as desired and also to one terminal of the winding of relay R, the other terminal of said winding being connected to the negative terminal of the battery B, the other

terminal of which battery is connected to the common conductor 33.

The relay 47 is provided with a third armature 68 connected by wire 69 through a cut-off switch 70 with one terminal of a drop 71, the other terminal of which is connected with the negative terminal of a battery 72, the other terminal of which battery is connected by wire 73 with the common conductor 33. The drop 71 is provided with a shutter 74 and make contact 75 connected with one terminal of the battery 76 and one terminal of the bell 77 respectively, the other terminals of the battery and bell being connected together, as a result of which when the drop is actuated the bell circuit is closed and it continues to ring an alarm until the drop is restored to its normal position shown in Fig. 1. The armature 68 is provided with a break-contact 78 connected by wire 79 with a third armature 80 of relay 50. The armature 80 is provided with a break-contact 81 connected by wire 82 with one of the contact springs 83 of the door mechanism, the coöperating spring 84 being connected with wire 56. The door has secured to it a plate 85 carrying a plug 86 which engages the spring 58 when the door is closed and separates said spring from the spring 57. A conducting plug 87 separate and insulated from the plate 85 is provided for engaging the springs 83 and 84 when the door is in its closed position, this plug being suitably mounted on the door casing so that it may occupy an outer position away from the springs 83 and 84 when the door is open and thus prevent closing the alarm circuit by the springs 57 and 58. Closing the door serves to move the plug 87 between the contacts 83 and 84, thus connecting them so that a subsequent opening of the door closes the alarm circuit by the engagement of the springs 57 and 58 since the plug 87 remains between and in contact with the springs 83 and 84 and thus electrically connects them. The door contact springs and the operating mechanism described constitute a part of the subject matter of my Patent Number 1,127,916, issued February 9, 1915, and therefore require no further illustration or description. The wire 69 may be extended if desired to the controlling mechanism and connected with an otherwise disconnected one of the contacts 14 so that an unauthorized person tampering with the controlling mechanism and pressing the dial rearwardly in a position corresponding to the contact with which the wire 69 is connected will operate the alarm. As a result of the connections described and assuming that the wires 30, 35 and 42 are connected respectively with the contacts 14 which are numbered 2, 5 and 7 on the dial plate and that the wires 69 and 67 are connected with the contacts 14 designated 9 and

8, 6 and 8 respectively on the dial plate, the operation of the system is as follows: The relays 31, 39, 47, 50 and R are normally deenergized, as a result of which if the plug 86 is removed from the contact spring 58 a circuit is closed through the winding of the drop 71 as follows: battery 72, winding 71, wire 69, switch 70, armature 68, contact 78, wire 79, armature 80, contact 81, wire 82, contact spring 83, plug 87, contact spring 84, spring 57, spring 58, wire 59, wire 73 back to battery 72. This closes the bell circuit and the alarm is sounded. To temporarily disable the alarm circuit so that closure of the springs 57 and 58 will not operate the alarm circuit just traced, a person desiring to enter the door first rotates the dial to the indication "2" and presses it rearwardly, which connects the conducting ring with the contact marked "2". As a result of this, since the common conductor 33 is connected with the contact numbered 14 and in turn with the conducting ring 15, a circuit is closed as follows: battery 32, wire 33, contact marked 14, conducting ring 15, contact blade of controlling mechanism, contact marked 2, wire 30, winding of relay 31, back to battery 32. As a result the armatures 34 and 36 are attracted and the relay 31 is maintained in energized condition through the following locking circuit: battery 32, wire 33, wire 88, armature r, wire 62', contact 60, contact 61, wire 62, contact 63, armature 34, winding of relay 31, back to battery 32. After depressing the dial in the position marked "2" with the results described, which of course occur as soon as the circuit is closed, the dial is permitted to move to its outer position and is rotated to the position marked 5, and again pushed inward, making connection between wires 33 and 35 through the contact blade of the controlling mechanism, which closes the following circuit: battery 40, wire 33 through the controlling mechanism to wire 35, armature 36, contact 37, wire 38, winding of relay 39, back to battery 40. As a result the armatures 41 and 43 are attracted and a locking circuit for the relay 39 is closed as follows: battery 40, wire 33, wire 88, armature r, wire 62', contact 60, contact 61, wire 62, contact 64, armature 41, winding of relay 39 back to battery 40. The operator now releases the dial and rotates it to the position marked 7, and again presses the dial rearwardly, which connects the contact marked 7 with the conducting ring 15, and thus electrically connects wires 33 and 42 and closes the following circuit: battery 51, wire 33, wire 42, armature 43, contact 44, wire 45, contact 48, armature 49, winding of relay 47 back to battery 51. As a result the armature 46 is attracted and closes a locking circuit for the relay 47 before separating the contact 60 and 61, this locking

circuit being as follows: battery 51, wire 33, wire 88, armature *r*, wire 62, contact 60, armature 46, wire 45, contact 48, armature 49, winding of relay 47, back to battery 51.

5 The separation of the contacts 60 and 61 opens the locking circuits above traced for the relays 31 and 39 as a result of which it will appear that the relay 47 is locked in energized condition before the relays 31 and 10 39 are released by the opening of their locking circuits. Besides closing a locking circuit for itself the energization of the relay 47 connects the battery 51 with the winding of the relay 50 so that said relay may later 15 be energized, and by attracting the armature 68 the energization of the relay 47 opens the alarm circuit above traced through the winding of the drop 71 and thus prevents the energization of the drop as long 20 as the relay 47 is energized. For this condition of the relay 47 the door may be opened without danger of closing the alarm circuit and when so opened the removal of the plug 86 from the contact spring 58 25 closes the following circuit: battery 51, wire 33, wire 59, spring 58, spring 57, wire 56, winding of relay 50, wire 54, contact 53, armature 52, back to battery 51. The energization of the relay 50 attracts the armature 49 and thus opens the locking circuit above traced for the relay 47, but since the relay 47 is of the slow acting type, the armature 52 does not leave the contact 53 until 30 after the armature 55 of the relay 50 has 35 been brought into engagement with the contact 65 to furnish a retaining circuit for the relay 50 as follows: battery 66, wire 33, wire 59, contact 58, contact 57, wire 56, winding of relay 50, armature 55, contact 65, back 40 to battery 66. The relay 50 is thus maintained in energized condition as long as the springs 57 and 58 remain in engagement with each other, or in other words, as long as the door is open, and for this condition the 45 armature 80 is attracted away from the contact 81, this operation having taken place before the armature 68 returned into engagement with the contact 78 and thus the energizing circuit of the drop 71 is maintained 50 in inoperative condition as long as the relay 50 is energized. When the door is closed the springs 57 and 58 are separated, thus opening the locking circuit of the relay 50, which thereupon returns to its normal condition 55 and the controlling system is again ready for operation. A means is thus provided for opening the door without actuating the alarm provided the controlling mechanism is properly manipulated which 60 can only be done by an authorized person who knows the combination, the effect being the same as though the operation of a combination lock were required to open the door without actuating the alarm. When a person 65 passes through the door and closes the

same he has access to the switch 70 by which he may cut off the alarm circuit before again opening the door and when he desires to leave, the conducting plug 87 is withdrawn, the cut-off switch 70 is closed and the door 70 is shut with the result that the alarm circuit is not closed by this operation for the reason that the spring 58 is removed from engagement with the spring 57 slightly in advance of the engagement of the contacts 75 83 and 84 by the plug 87. The connection of the release wire 67 with desired ones of the contacts 14 results in energization of the relay *R* if the dial is depressed in either of the positions marked 3, 6 and 8 for the connections indicated in Fig. 1, since if the dial is depressed in either of these positions the wires 33 and 67 are electrically connected in the controlling mechanism. This energization circuit is as follows: battery *B*, 80 wire 33 through the controlling mechanism to wire 67, winding of relay *R* back to battery *B*. As a result of the energization of the relay *R* and the moving of the armature *r* away from its contact the locking circuit 90 through the relays 31 and 39 is opened and these relays are restored to their normal condition, and if for this condition the switch of the controlling mechanism is moved into position to connect the wires 33 95 and 42 the relay 47, will not be energized since the armature 43 is away from its contact. Similarly if prior to the energization of the relay *R* the relays 31, 39 and 47 have been energized and thus the relay 47 has 100 been locked in its actuated position the energization of the relay *R* opens the locking circuit of the relay 47, restoring it to its normal condition. It therefore follows that whether one, two or all of the relays 31, 39 105 and 47 have been energized prior to the energization of the relay *R*, this operation of the relay *R* restores or releases such of the relays 31, 39 and 47 as may have been energized and held in locked condition. The 110 safety springs 27 and 28 are connected respectively by wires 89 and 90 with wires 33 and 69, as a result of which if it be attempted to remove the controlling mechanism from its casing 10 a circuit is closed 115 through the drop 71 as above described for operation of the controlling mechanism in the position marked 9 and the alarm is sounded. While I have shown but two relays 31 and 39 which must be operated in sequence before it is possible to operate the relay 47, it will be understood that a greater number of such relays may be employed if desired, or if preferred the relay 39 may be eliminated and the relay 31 may be made 120 to control the operation of the relay 47 as said operation is controlled in Fig. 1 by the relay 39.

While several batteries are shown in the system illustrated in Fig. 1, it will be un- 130

derstood that the entire system may be operated from one battery if desired, such an arrangement being shown in the modified system shown in Fig. 2, which is similar to the system shown in Fig. 1, with the exception that the alarm circuit is normally closed instead of being normally open. In this modified construction the relays 31, 39, 47, 50 and R are similarly constructed and operated through wires 30, 35, 42 and 67 from the controlling mechanism, the principal difference being that a single battery 91 is employed, to one terminal of which the common conductor 33 is connected and to the other terminal of which a common conductor 92 is connected, which in turn is connected by wires 93, 94, 95, 96^a and 96' with the windings of the relays 31, 39, 47, contact 65 and winding of relay R respectively instead of the similarly connected batteries 32, 40, 51, 66 and B as shown in Fig. 1. In this modification the bell 77 has one terminal connected by wire 97 with the common conductor 33 and the contact 75 is connected by wire 98 with the other common conductor 92, the shutter 74 of the drop being connected with the other terminal of the bell 77.

In this modification the alarm circuit is different from that above described in that it is normally closed and must be broken in order to operate the alarm. This alarm circuit may be traced as follows: battery 91, wire 92, wire 93, safety spring 28^a, safety spring 27^a, wire 94' to winding of drop 71, cut-off switch 70, wire 95', wire 96, contact spring 57, contact spring 58, wire 97, wire 98, wire 33 back to battery 91. The contact 84^a is connected with the contact 57 and the contact 83^a is connected with the contact 58 through wire 97. In this modification the plug 87^a is of insulating material and normally prevents contact between the springs 83^a and 84^a when the door is closed, for which position of the door the plug 86 maintains the spring 58 in engagement with the spring 57. When plug 87^a is withdrawn the springs 83^a and 84^a engage each other, thus maintaining the drop energized so that the removal of the plug 86 from the spring 58 will not operate the alarm. The cut-off switch 70 is provided with an alternate contact 99 connected by wire 100 with wire 33, the contacts of this switch being close enough together so that one is made before the other is broken in the operation of the switch in order that the circuit through the energizing winding of the drop 71 may remain closed while the switch is being moved from one position to the other. In this modification the armatures 68 and 80 of the relays 47 and 50 respectively coöperate with make-contacts 78 and 81 connected together and by wire 101 with common conductor 33, the armatures 68^a and 80 being connected to wire

96. As a result of the circuit connections described the energization of either the relay 47 or 50, by attracting the armature 68 or 80, as the case may be, maintains the alarm circuit in closed condition, or in other words prevents the operation of the alarm which is the same result as is described for the system shown in Fig. 1 for the energization of the relays 47 and 50. The separation of the safety springs 27^a and 28^a from each other in the modified construction shown in Fig. 2 opens the alarm circuit, thus ringing the alarm so that for this modification protection may be secured against tampering with the control mechanism in substantially the same manner as described above for the system shown in Fig. 1.

In the modified system shown in Fig. 3 my controlling mechanism is adapted to control the ignition circuit of an automobile shown diagrammatically in this figure of drawings. In this modification the secondary winding 105 of the induction coil 106 has one of its terminals connected by wire 107 with the distributing switch 108, the contacts 109 of which are connected by wires 110 with the spark plugs 111 of the several cylinders of the engine, the casing 112 of which is connected by wire 113 with the other terminal of the secondary winding 105. The primary winding 114 of the induction coil 106 has one of its terminals connected with the vibrator 115, the other terminal of the primary winding being connected by wire 116 with the contact 117 of the control switch 118. The contact 119 of the vibrator mechanism is connected by wire 120 through switch 121 with one terminal of the battery 122, the other terminal of which battery is connected by wire 123 with the switch 118. The switch 121 may be of any desired kind and preferably represents a key operated switch well known in the art, which provides that the switch may only be operated by means of a suitable key, thus preventing to a degree the closing of the ignition circuit by an unauthorized person. In practice, however, it is found that such a key switch does not afford a full measure of protection as a result of which it is frequently desirable to use a further means of protection, such, for example, as that afforded by the switch 118 which is automatically controlled by my control mechanism. This control mechanism as herein employed consists of the relays 31^b and 39^b operated by the control mechanism 124 in precisely the manner described above for the relays 31 and 39. Battery current is supplied for the operation of the relays 31^b and 39^b through the common conductors 92^b and 33^b from the battery 122 in the same manner that current is supplied to the relays 31 and 39 from the battery 91 in Fig. 2. The switch 118 is pivotally mounted at 125 and is pro-

vided with a slot 126 through which a pin 127 projects, said pin being carried by a rod 128 constituting the core of the solenoids 129 and 130. The terminals of the winding of the solenoid 129 are connected by wires 131 and 132 with the common conductor 92^b and the contact 44^b of the armature 43^b respectively. The terminals of the winding of the solenoid 130 are connected by wires 133 and 134 with a desired one of the contacts of the controlling mechanism 124 and with the common conductor 92^b respectively. The contacts 63^b and 64^b coöperating with the armatures 34^b and 41^b are connected together by wire 62^b and to the contact 135, which is in engagement with the contact spring 136 when the ignition circuit is open at the switch 118. The contact 136 is connected by wire 137 with the switch pivot 125. The contact spring 136 tends at all times to move from engagement with the contact spring 135 and when these contact springs are in engagement with each other they are held in such position by a pin 138 engaging the contact spring 136, said pin being carried by the rod 128. The rod 128 is supported so as to move freely in the solenoids 129 and 130 by suitable non-magnetic guides 139 and 140, the solenoids, the switch 118 and the contact springs 135 and 136 being suitably mounted in a closed box inaccessible except to one having a key to said box. The guide 140 is secured to one wall 141 of the inclosing casing through which wall an aperture 35 is formed in line with the rod 128, said aperture being somewhat smaller than the bore of the guide 140 and through this aperture a plug 142 projects having an operating head on its outer end and an enlarged head on its inner end for retaining it in place in the solenoid 129. The switch 118 is preferably provided with a retaining spring 143 for holding it in its open position. As a result of the construction described after the relays 31^b and 39^b have been operated in the manner described above for Figs. 1 and 2 and the third operating impulse is sent by the controlling mechanism through wire 42^b the solenoid 129 is energized through the following circuit: battery 122, wire 92^b, wire 131, winding of solenoid 129, wire 132, contact 44^b, armature 43^b, wire 42^b through the controlling mechanism 124 to wire 33^b and thus back to battery 122. This moves the rod 128 to the right, thus moving the switch 118 in engagement with the contact 117 and closing the ignition circuit through the primary winding 114 of the induction coil assuming that the key-operated switch 121 has been previously closed. The movement of the rod 128 to the right as shown in Fig. 3 also permits the contact spring 136 to move from engagement with the contact 135, thus opening the locking circuit of the relays 31^b and 39^b. The construction of the

parts, however, is such that the locking circuit is not opened until the switch 118 is in engagement with the contact 117, a stop 135^a being provided to engage the contact spring 135 immediately after the spring 126 engages its contact 117. When it is desired to render the ignition circuit inoperative for a time the controlling mechanism 124 may be used to send current through the winding of the solenoid 130 over the following circuit by moving the dial of the controlling mechanism to a position corresponding with the contact to which the wire 133 is connected and then pushing the dial to the rear as above described: battery 122, wire 92^b, wire 134, winding of solenoid 130, wire 133 through the controlling mechanism 124 to wire 33^b and thus back to battery 122. This serves to move the bar 128 to the left as a result of which the switch 118 is moved from engagement with its contact 117, and the ignition circuit is opened in which position the switch and rod 128 are held by the spring 143. This same operation moves the pin 138 into engagement with the contact spring 136, thus moving said spring into engagement with the contact 135, closing the locking circuit above referred to for the relays 31^b and 39^b. If preferred the rod 128 may be moved to the left to open the ignition circuit by means of the plug 142 without the use of the controlling mechanism 124.

As a result of the construction above described it will be observed that by my invention I have provided controlling mechanism such that a plurality of devices must be operated in a predetermined sequence in order that a desired electric circuit may be opened or closed as desired by the operation of the controlling system as a whole, and furthermore that the switching mechanism forming a part of my controlling mechanism affords a means for a plurality of positions, indicated numerically or otherwise, to which the switching mechanism must be moved in the predetermined sequence to properly operate the electrical part of the controlling mechanism. It will be understood that the dial may either have numerals or letters or any other indicating characters to guide in selecting different conditions for operating the controlling mechanism, and that these indicating characters may be placed in any manner upon or around the dial that will afford a guide to locating the dial definitely in different angular positions. From the above it will appear that the controlling mechanism of my system may be called a combination control, for the reason that from a plurality of possible positions of the controlling mechanism by which the operation of the system is initiated certain positions must be selected in predetermined order to properly secure the successive operations of

the controlling system so that the ultimate control exercised by the system may be effected and that the particular positions of operation may be changed as desired to 5 meet varying conditions so that no two systems may have the same combination.

It will be understood in connection with the systems shown in Figs. 1 and 2 that the release wire 67 and the relay operated there- 10 by may be omitted if desired as may also the ringing wire 69 and that other arrangements of controlling relays may be employed as long as it is necessary to operate the controlling relays in predetermined order or 15 relation to each other so that the circuit controlled by the system may be opened or closed as desired by the subsequent operation of another relay or electromagnetic device.

20 It will be understood that I do not limit myself in carrying out my invention to the particular embodiments above described as I may employ equivalents thereof without departing from the spirit of my invention.

25 What I claim is:

1. A control system of the type described comprising in combination, an alarm circuit, a plurality of electromagnetic devices, operating circuits for said devices each con- 30 trolled by the operation of a preceding one of said devices in the sequence of operation of said devices, contacts operated by the last one of said devices in said sequence of operation for controlling the closure of said 35 alarm circuit, a switching mechanism having a plurality of operative positions, one for operating each of said devices and other inoperative positions, whereby said devices are operated to control the closure of said circuit only when said switching mechanism is moved successively to the several positions controlling said devices in their predetermined sequence of operation and electric devices controlled by said alarm circuit for giving 40 an alarm.

2. A control system of the type described comprising in combination, an alarm circuit, a plurality of electromagnetic devices, operating circuits for said devices each con- 50 trolled by the operation of a preceding one of said devices in the sequence of operation of said devices, contacts operated by the last one of said devices in said sequence of operation for controlling the closure of said 55 alarm circuit, a switching mechanism having a plurality of operative positions, one for operating each of said devices and other inoperative positions, whereby said devices are operated to control the closure of said 60 circuit only when said switching mechanism is moved successively to the several positions controlling said devices in their predetermined sequence of operation, said switching mechanism comprising a circular dial, a 65 switch blade and contacts for engagement

with said switch blade, said dial being movable in one direction to select a desired contact and in another direction to bring said contact blade into engagement with the selected contact and electric devices controlled 70 by said alarm circuit for giving an alarm.

3. A control system of the type described comprising in combination, an alarm circuit, a plurality of relays each controlling the operating circuit of another in a predeter- 75 mined sequence, contacts carried by the last relay in said sequence for controlling the closure of said alarm circuit, switching mechanism having contacts and operating circuits extending each from a desired one of 80 said contacts to operate said relays, there being a greater number of said contacts than operating circuits whereby said switching mechanism must be selectively operated in predetermined sequence to select the contacts 85 connected with said operating circuits to properly operate said relays in the necessary sequence to control the closure of the desired circuit and electric devices controlled by said alarm circuit for giving an alarm.

4. A control system of the type described comprising in combination, an alarm circuit, a plurality of relays each controlling the operating circuit of another in a predeter- 95 mined sequence, contacts carried by the last relay in said sequence for controlling the closure of said alarm circuit, switching mechanism having contacts and operating circuits extending each from a desired one of 100 said contacts to operate said relays, there being a greater number of said contacts than operating circuits whereby said switching mechanism must be selectively operated in predetermined sequence to select the contacts connected with said operating circuits to 105 properly operate said relays in the necessary sequence to control the closure of the desired circuit, said switching mechanism comprising a rotary disk having a switch 110 blade for engagement with said contacts and indicating characters for determining different angular positions of said disk and switch blade corresponding to the several contacts, said disk being movable axially to bring said switch blade into engagement 115 with a selected contact and electric devices controlled by said alarm circuit for giving an alarm.

5. A control system of the type described comprising in combination, an alarm circuit, a plurality of electromagnetic devices, operating circuits for said devices each controlled by the operation of a preceding one of said devices in the sequence of operation of said devices, contacts operated by the last one of said devices in said sequence of operation for controlling the closure of said alarm circuit, a switching mechanism having a 120 plurality of operative positions, one for operating each of said devices and other inop- 125

erative positions, whereby said devices are operated to control the closure of said circuit only when said switching mechanism is moved successively to the several positions controlling said devices in their predetermined sequence of operation, a release circuit extending from said switching mechanism for restoring said electromagnetic devices to normal condition and electric devices controlled by said alarm circuit for giving an alarm.

6. A control system of the type described comprising in combination, an alarm circuit, a plurality of relays each controlling the 15 operating circuit of another in a predetermined sequence, contacts carried by the last relay in said sequence for controlling the closure of said alarm circuit, switching mechanism having contacts and operating 20 circuits extending each from a desired one of said contacts to operate said relays, there being a greater number of said contacts than operating circuits whereby said switching mechanism must be selectively 25 operated in predetermined sequence to select the contacts connected with said operating circuits to properly operate said relays in the necessary sequence to control the closure of the desired circuit, a release 30 circuit extending from said switching mechanism for restoring said relays to normal condition and electric devices controlled by said alarm circuit for giving an alarm.

7. A control system of the type described 35 comprising in combination, an alarm circuit, a plurality of electromagnetic devices, operating circuits for said devices each controlled by the operation of a preceding one of said devices in the sequence of operation 40 of said devices, contacts operated by the last one of said devices in said sequence of operation for controlling the closure of said alarm circuit, a switching mechanism having a plurality of operative positions, one 45 for operating each of said devices and other inoperative positions, whereby said devices are operated to control the closure of said circuit only when said switching mechanism is moved successively to the several 50 positions controlling said devices in their predetermined sequence of operation, a locking circuit for each electromagnetic device for maintaining it in operated condition when actuated and electric devices controlled by 55 said alarm circuit for giving an alarm.

8. A control system of the type described comprising in combination, an alarm circuit, a plurality of relays each controlling the operating circuit of another in a predetermined sequence, contacts carried by the 60 last relay in said sequence for controlling the closure of said alarm circuit, switching mechanism having contacts and operating circuits extending each from a desired one 65 of said contacts to operate said relays, there

being a greater number of said contacts than operating circuits whereby said switching mechanism must be selectively operated in predetermined sequence to select the contacts connected with said operating circuits 70 to properly operate said relays in the necessary sequence to control the closure of the desired circuit, a locking circuit for each relay for maintaining it in operated condition when actuated and electric devices controlled by said alarm circuit for giving an alarm.

9. A control system of the type described comprising in combination, an alarm circuit, a plurality of electromagnetic devices, operating circuits for said devices each controlled by the operation of a preceding one of said devices in the sequence of operation of said devices, contacts operated by the last one of said devices in said sequence of 85 operation for controlling the closure of said alarm circuit, a switching mechanism having a plurality of operative positions, one for operating each of said devices and other inoperative positions, whereby said devices 90 are operated to control the closure of said circuit only when said switching mechanism is moved successively to the several positions controlling said devices in their predetermined sequence of operation, a locking 95 circuit for each electromagnetic device for maintaining it in operated condition when actuated, contacts operated by the last electromagnetic device in said sequence when actuated for opening the locking circuits of 100 the preceding electromagnetic device in said sequence and electric devices controlled by said alarm circuit for giving an alarm.

10. A control system of the type described comprising in combination, an alarm circuit, a plurality of relays each controlling the operating circuit of another in a predetermined sequence, contacts carried by the last relay in said sequence for controlling the closure of said alarm circuit, switching mechanism having contacts and operating circuits extending each from a desired one of said contacts to operate said relays, there being a greater number of said contacts than operating circuits whereby said switching 110 mechanism must be selectively operated in predetermined sequence to select the contacts connected with said operating circuits to properly operate said relays in the necessary sequence to control the closure of the 115 desired circuit, a locking circuit for each relay for maintaining it in operated condition when actuated, contacts operated by the last relay in said sequence when actuated for opening the locking circuits of the preceding relays in said sequence and electric devices controlled by said alarm circuit for giving an alarm.

11. A control system of the type described comprising in combination, an alarm circuit, 130

a first relay, switching mechanism having a plurality of operative positions and a corresponding number of operative contacts, a first operating circuit extending from said

5 relay to one of said contacts, a second relay, a second operating circuit extending from said second relay through contacts on said first relay to a second one of the operative contacts of said switching mechanism, contacts operated by said second relay for determining the closure of said alarm circuit, idle contacts on said switching mechanism whereby the operative contacts must be selected and closed in predetermined sequence

10 to operate said second relay, a locking circuit for said first relay extending through contacts on said second relay whereby when said second relay is operated said locking circuit is opened and electric devices controlled by said alarm circuit for giving an alarm.

12. A control system of the type described comprising in combination, an alarm circuit, a plurality of control relays arranged for a predetermined sequence of operation, each of said relays after the first in said sequence having its operating circuit extending through contacts on the relay preceding it in said sequence, switching mechanism having 30 contacts one for each relay connected to the corresponding operating circuits of said relays, contacts operated by the last control relay in said sequence for determining the closure of said alarm circuit, idle contacts on said switching mechanism whereby the operative contacts must be selected and closed by said switching mechanism in certain order to operate said control relays in said predetermined sequence, locking circuits for 40 said relays, contacts carried by the last relay in said sequence for opening the locking circuits of the preceding relays when said last relay is operated and electric devices controlled by said alarm circuit for giving an alarm.

13. A control system of the type described comprising in combination, an alarm circuit, a plurality of control relays arranged for a predetermined sequence of operation, each 50 of said relays after the first in said sequence having its operating circuit extending through contacts on the relay preceding it in said sequence, switching mechanism having contacts one for each relay connected to the corresponding operating circuits of said relays, contacts operated by the last control relay in said sequence for determining the closure of said alarm circuit, idle contacts on said switching mechanism whereby the operative contacts must be selected and closed by said switching mechanism in certain order to operate said control relays in said predetermined sequence, a release relay 60 for restoring by its operation said control 65 relays, a release circuit extending from said

release relay to one of the contacts of said switching mechanism and electric devices controlled by said alarm circuit for giving an alarm.

14. A control system of the type described comprising in combination, an alarm circuit, a plurality of electromagnetic devices, operating circuits for said devices each controlled by the operation of a preceding one of said devices in the sequence of operation 75 of said devices, contacts operated by the last one of said devices in said sequence of operation for controlling the closure of said alarm circuit, a switching mechanism having a plurality of operative positions, one for operating each of said devices and other inoperative positions, whereby said devices are operated to control the closure of said circuit only when said switching mechanism is moved successively to the several positions 80 controlling said devices in their predetermined sequence of operation, a locking circuit for each electromagnetic device for maintaining it in operated condition when actuated, a release relay operated by said 85 switching mechanism for opening said locking circuits and electric devices controlled by said alarm circuit for giving an alarm.

15. A control system of the type described comprising in combination, an alarm circuit, 95 a plurality of relays each controlling the operating circuit of another in a predetermined sequence, contacts carried by the last relay in said sequence for controlling the closure of said alarm circuit, switching mechanism 100 having contacts and operating circuits extending each from a desired one of said contacts to operate said relays, there being a greater number of said contacts than operating circuits whereby said switching mechanism must be selectively operated in predetermined sequence to select the contacts connected with said operating circuits to properly operate said relays in the necessary sequence to control the closure of the 105 desired circuit, a locking circuit for each relay for maintaining it in operated condition when actuated, a release relay operated by said switching mechanism for opening said locking circuits and electric devices controlled by said alarm circuit for giving an 110 alarm.

16. A control system of the type described comprising in combination, an alarm circuit, a plurality of relays each controlling the 120 operating circuit of another in a predetermined sequence, contacts carried by the last relay in said sequence for controlling the closure of said alarm circuit, switching mechanism having contacts and operating circuits 125 extending each from a desired one of said contacts to operate said relays, there being a greater number of said contacts than operating circuits whereby said switching mechanism must be selectively operated in pre- 130

- determined sequence to select the contacts connected with said operating circuits to properly operate said relays in the necessary sequence to control the closure of the alarm circuit, door contacts in said alarm circuit, and a cut-off relay actuated by the operation of said door contacts for controlling by its operation the closure of said alarm circuit.
17. A control system of the type described comprising in combination, an alarm circuit, a plurality of relays each controlling the operating circuit of another in a predetermined sequence, contacts carried by the last relay in said sequence for controlling the closure of said alarm circuit, switching mechanism having contacts and operating circuits extending each from a desired one of said contacts to operate said relays, there being a greater number of said contacts than operating circuits whereby said switching mechanism must be selectively operated in predetermined sequence to select the contacts connected with said operating circuits to properly operate said relays in the necessary sequence to control the closure of the alarm circuit, a locking circuit for each relay for maintaining it in operated condition when actuated, door contacts in said alarm circuit, and a cut-off relay actuated by the operation of said door contacts for controlling by its operation the closure of said alarm circuit.
18. A control system of the type described comprising in combination, an alarm circuit, a plurality of relays each controlling the operating circuit of another in a predetermined sequence, contacts carried by the last relay in said sequence for controlling the closure of said alarm circuit, switching mechanism having contacts and operating circuits extending each from a desired one of said contacts to operate said relays, there being a greater number of said contacts than operating circuits whereby said switching mechanism must be selectively operated in predetermined sequence to select the contacts connected with said operating circuits to properly operate said relays in the necessary sequence to control the closure of the alarm circuit, a locking circuit for each relay for maintaining it in operated condition when actuated, door contacts in said alarm circuit, and a cut-off relay actuated by the operation of said door contacts for controlling by its operation the closure of said alarm circuit, said last operated relay being sluggish in operation whereby the control of the alarm circuit exercised by it is retained until after said cut-off relay exercises its control over said alarm circuit.
19. A control system of the type described comprising in combination, an alarm circuit, a control relay, switching mechanism for operating said relay, contacts actuated by said relay for controlling the closure of said alarm circuit, door contacts in said

alarm circuit, a cut-off relay actuated by the operation of said door contacts, contacts operated by said cut-off relay for controlling the closure of said alarm circuit, and a locking circuit for said control relay controlled by said cut-off relay whereby the operation of said cut-off relay opens said locking circuit, said control relay being sluggish in operation as compared with said cut-off relay so that the control of the latter over the alarm circuit is exercised before the corresponding control of the control relay is relinquished.

20. A control system of the type described comprising in combination, an alarm circuit, a plurality of electromagnetic devices, operating circuits for said devices each controlled by the operation of a preceding one of said devices in the sequence of operation of said devices, contacts operated by the last one of said devices in said sequence of operation for controlling the closure of an electric circuit, a switching mechanism having a plurality of operative positions, one for operating each of said devices and other inoperative positions, whereby said devices are operated to control the closure of said circuit only when said switching mechanism is moved successively to the several positions controlling said devices in their predetermined sequence of operation, and safety contact springs carried by the housing of said switching mechanism, said alarm circuit extending through said safety contact springs, whereby an attempt to dismantle said switching mechanism results in operating said safety contact springs and actuating said alarm circuit.

21. A control system of the type described comprising in combination, an alarm circuit, a plurality of relays each controlling the operating circuit of another in a predetermined sequence, contacts carried by the last relay in said sequence for controlling the closure of an electric circuit, and switching mechanism having contacts and operating circuits extending each from a desired one of said contacts to operate said relays, there being a greater number of said contacts than operating circuits whereby said switching mechanism must be selectively operated in predetermined sequence to select the contacts connected with said operating circuits to properly operate said relays in the necessary sequence to control the closure of the desired circuit, and safety contact springs carried by the housing of said switching mechanism, said alarm circuit extending through said safety contact springs whereby an attempt to dismantle said switching mechanism results in operating said safety contact springs and actuating said alarm circuit.

22. A control system of the type described comprising in combination, an alarm circuit,

5 a control relay, contacts actuated by said relay for controlling the closure of said alarm circuit, a door, contacts operated by said door and located in said alarm circuit, a cut off relay actuated by the operation of said door contacts during the opening of said door, and contacts operated by said cut off relay for controlling the closure of said alarm circuit, said control relay controlling by its operation the operation of 10 said cut-off relay.

15 23. In combination, a casing for containing switching mechanism, said casing having a removable front plate and an insulating plate inside of said casing carried by said front plate, spring contacts carried by said insulating plate, an alarm circuit connected with said contacts and extending to a point remote from said casing, alarm 20 mechanism connected with said circuit at said remote point, said contacts being operated by the wall of said casing when said front plate is in place to disable said contacts, whereby removing said front plate 25 causes operation of said contacts and of said alarm mechanism.

24. A control system of the type described comprising in combination, an alarm circuit, door contacts connected with said circuit 30 for causing operation of said circuit, a control relay for disabling the control of said alarm circuit by said contacts, means for operating said control relay, and a cut-off relay operated by said door contacts for 35 also disabling the control of said alarm circuit by said contacts, said control relay controlling by its operation the operation of said cut-off relay.

25. A control system of the type described 40 comprising in combination, an alarm circuit, contacts connected with said circuit for causing operation of said circuit, a control relay for disabling the control of said contacts, means for operating said control relay, door contacts, a cut-off relay operated 45 by said door contacts for also disabling the control of the first mentioned contacts, and an operating circuit for said cut-off relay extending through said door contacts and 50 also through contacts on said control relay.

26. A control system of the type described comprising in combination, an alarm circuit, contacts connected with said circuit for causing operation of said circuit, a control relay for disabling the control of said contacts, means for operating said control relay, door contacts, a cut-off relay operated by said door contacts for also disabling the control of the first mentioned contacts, an operating circuit for said cut-off relay extending through said door contacts and also through contacts on said control relay, and an operating circuit for said control relay extending through contacts of said cut-off relay. 55 60 65

27. A control system of the type described comprising in combination, an alarm circuit, contacts connected with said circuit for causing operation of said circuit, a control relay for disabling the control of said contacts, means for operating said control relay, door contacts, a cut-off relay operated by said door contacts for also disabling the control of the first mentioned contacts, an operating circuit for said cut-off relay extending through said door contacts and also through contacts on said control relay, and a locking circuit for said control relay extending through contacts of said cut-off relay. 70 75 80

28. A control system of the type described comprising in combination, an alarm circuit, contacts connected with said circuit for causing operation of said circuit, a control relay for disabling the control of said contacts, a series of relays arranged in sequence, an operating circuit for each of said series of relays except the first in said sequence extending through contacts of the preceding relay in said sequence, an operating circuit for said control relay extending through contacts of the last of said series of relays, a locking circuit for each of said series of relays, and a release relay having contacts in said locking circuits for opening the 85 90 95 same.

In witness whereof, I hereunto subscribe my name this 21st day of January A. D. 1916.

THEODORE H. NELSON.
